UNITED STATES PATENT OFFICE

EDWARD L. HOFFMAN, OF DAYTON, OHIO

COMBINATION PARACHUTE HARNESS

Application filed June 14, 1930. Serial No. 461,191.

2, a seat type pack 11 and a back type pack 12. The harness comprises essentially a suspension rigging which consists of main lift webs or riser straps 13 and 14, of which there are 5 eight in number, four for each type of pack used, and which are divided into pairs as shown in Fig. 1 two pairs being used for each type of pack used. Each individual riser strap is secured to the suspension lines of 10 their respective parachute by means of suitable connector rings 15 and 16 respectively. It will be noted that the suspension lines of each parachute are divided into a plurality of groups in the present instance, as aforementioned, there being four in each group of 15 suspension lines having their lower ends fastened to the connector rings in a manner clearly shown. Before the opening of the parachute the lift webs extend into their respective packs in which the parachutes are 20 folded as indicated in Fig. 2.

Each main lift web is made of two-ply fabric material or webbing of double thickness which emerge in pairs from adjacent 25 corners of their respective packs as shown, forming a top and bottom lift strap respectively. Each pair of lift straps, as will be noted by referring to Fig. 1 of the drawings, pass up the wearer's back and over the shoulders, at which point they are threaded 30 through oblong shoulder adapter rings 18 and 19 respectively. The main lift webs of the seat pack designated by numerals 20 and 21 are thereafter passed downwardly at the 35 front and sides of the chest of the aviator to a point adjacent the hips. The lift straps of each pair are separated at this point, each top and bottom strap extending inwardly and under the legs of the aviator as shown 40 in Figs. 1 and 2. Each top strap 20 is of greater length than its correlated bottom strap and terminates in one member 22 of a separable fastener to form one portion of the leg strap. The bottom strap of each lift web 45 is formed with a looped end 23 adapted to receive the top strap of its opposite correlated leg strap in the manner shown, to form a seat support adapted to sustain the weight of the aviator.

50 Back straps 24 and 25 are provided, which are connected at their upper ends to the shoulder adapter rings 18 and 19 respectively. The left back strap designated by numeral 24 is connected to the left shoulder adapter 55 ring 18, thence extending diagonally downward across the back of the aviator where it passes around the outside of the opposite lift web 13, loops through the inner and outer ply of the top strap 20 and continues downward, 60 where it is threaded through the female member 26 of the separable fastener heretofore mentioned, forming a looped end, and thence returning around the lift web and laterally across the back of the wearer above the hips 65 where it is threaded through an adjusting

fitting 27, as will be apparent from the construction shown in Fig. 1.

The right back strap 25 in a similar manner is connected to the opposite shoulder adapter ring 19, extends diagonally downward across the back to the outside of the opposite main lift web in the same manner as described for the left back strap, threaded through the male member 29 of a second separable fastener and thence returns around the 75 main lift web, thereafter being connected to the central bar 30 of the adjusting fitting 27, heretofore mentioned. It will thus be seen that by adjusting the length of the back straps to fit the wearer's body a simultaneous 80 adjustment of each leg strap is obtained.

Threaded to the main lift webs 13 and 14 by means of loops sewed at their ends are chest straps 32 and 33 so arranged that the looped portions referred to may be slid up or down on the lift webs to adjust for the differences in height of different aviators. The chest straps are provided with male and female members 34 and 35 of a separable fastener adapter to connect the straps across the 90 chest of the wearer.

Intermediate the main lift webs on either side of the harness are sewed reinforced loops 36 shown in detail in Fig. 5, to which the riser straps 37 and 38 of the back pack may 95 be detachably secured by means of metallic fittings 39 which comprise plates 39a and 39b. As will be noted the plate 39a is provided with threaded portions at its upper and lower ends, the plate 39b having counterbored 100 openings which register with the threaded portions of the plate 39a. Machine screws are provided for securing the plates together. In attaching the lift straps 38 to the harness body, the lower machine screw is passed 105 through the loop 36 provided in the main lift straps, the upper bolt serving as a means for securing the lift strap 38 thereto, as shown in Figs 5 and 6. In so doing the risers 37 and 38 are first passed through the rings 18 and 19 on top of the risers for the seat pack and thereafter threaded through the loops 39 of the breast straps heretofore mentioned.

110 The back pack may be further secured to the harness by means of an auxiliary strap 40 secured to the end of the pack. This auxiliary strap is provided at either end with loops 41 through which the thigh straps of the harness are passed, the foregoing serving 115 the purpose of retaining the pack to the harness after the parachute is released.

120 The rip cord and handle 42 of the seat pack may be secured to the harness in any conventional manner as shown in Fig. 2, while the rip cord and handle 43 of the back pack is 125 passed beneath the left rear riser strap of the seat pack and carried around the left shoulder and secured to the main left strap.

125 While I have illustrated and described the preferred form of construction for carrying

- my invention into effect it is to be understood that variations and modifications may be made without departing from the spirit of the invention. I therefore do not wish to be limited to the precise detail of construction set forth, but desire to avail myself of such variations and modifications as may come within the scope of the appended claims.
- Having thus described my invention, what I claim as new and desire to secure by Letters Patent is:
1. A parachute body harness comprising a double set of main lift straps, each set adapted for attachment to an individual parachute pack, one of said sets of main lift straps including means adapted for ready attachment to or detachment from said body harness to provide a double parachute pack arrangement.
  2. A parachute body-harness comprising a double set of main lift straps, one set adapted for attachment to a back type parachute pack and the other set adapted for attachment to a seat type parachute pack respectively, said first-mentioned set including means adapted for ready attachment to or detachment from said body harness to provide a double parachute pack arrangement.
  3. A parachute body harness comprising a double set of main lift straps, one set adapted for attachment to a back type parachute pack and the other set adapted for attachment to a seat type parachute pack respectively, so constructed and arranged as to provide a double parachute pack arrangement, one set of lift straps being readily attachable to or detachable from said harness.
  4. In apparatus of the class described, in combination, a single parachute body harness having main supporting straps adapted to support the body of an aviator, a parachute pack connected to said harness, and means including a set of auxiliary supporting straps adapted for ready attachment to or detachment from said main supporting straps for readily attaching or detaching an emergency pack thereto to provide a double pack arrangement.
  5. In apparatus of the class described, in combination, a parachute body harness having main supporting straps adapted to support the body of an aviator, a seat type parachute pack connected to said straps, and means including a set of auxiliary supporting straps cooperating with said main supporting straps for readily attaching or detaching a back type parachute pack thereto whereby to provide a single and/or combination seat and back type pack arrangement in the manner and for the purpose described.
  6. A parachute harness comprising a plurality of main lift straps arranged in pairs and adapted for attachment to a parachute, the lower end of each pair of lift straps terminating in a leg strap and a seat strap, respectively, so constructed and arranged with respect to one another, to form a seat support for the wearer.
  7. A parachute harness comprising a plurality of main lift straps arranged in pairs and adapted for attachment to a parachute at their upper ends, each pair of lift straps terminating at their lower ends in a leg strap and a seat strap, respectively, the leg strap of each pair being connected to the opposite seat strap thereby to form a seat support for the wearer.
  8. A parachute harness comprising a plurality of main lift straps arranged in pairs and adapted for attachment to a parachute at their upper ends, each pair of lift straps terminating at their lower ends in a leg strap, and a seat strap respectively, the leg strap of each pair being yieldably connected to the opposite seat strap whereby to form a seat support adjustable to the seat of the wearer.
  9. A parachute harness comprising a plurality of main lift straps arranged in pairs and adapted for attachment to a parachute at their upper ends, each pair of lift straps terminating at their lower ends in a leg strap, and a seat strap having a looped portion, the leg strap of each pair being threaded through the looped portion of the opposite seat strap to provide a seat support adjustable to the seat of the wearer.
  10. A parachute harness comprising a plurality of main lift straps arranged in pairs and adapted for attachment to a parachute, each pair of lift straps extending in front of the chest of the aviator and terminating in a leg strap and a seat strap respectively, the leg strap of each pair being connected to the opposite seat strap to form a seat support for the wearer, and body supporting means comprising straps adjustably connected to said main lift straps to compensate for difference in stature of different aviators.
  11. A parachute harness comprising a plurality of main lift straps arranged in pairs and adapted for attachment to a parachute, each pair of lift straps extending in front of the chest of the aviator and terminating in a leg strap and a seat strap respectively, the leg strap of each pair being connected to the opposite seat strap to provide a seat support for the aviator, and chest straps connected to said lift strap having fastening means thereon to permit said straps being joined together across the aviator's chest to secure him within said harness.
  12. A parachute harness comprising a plurality of main lift straps arranged in pairs and adapted for attachment to a parachute, each pair of lift straps extending in front of the chest of the aviator and terminating in a leg strap and a seat strap respectively, the leg strap of each pair being connected to the opposite seat strap to provide a seat support for the aviator, a plurality of back straps

connected to the upper portion of said main lift straps, each back strap extending diagonally across the wearer's back and terminating in a thigh strap adapted to be connected to said leg straps and quickly releasable fastening means for securing said thigh straps to said leg straps whereby to encircle the legs of the aviator.

13. A parachute harness comprising a plurality of main lift straps arranged in pairs and adapted for attachment to a parachute, each pair of lift straps extending in front of the chest of the aviator and terminating in a leg strap and a seat strap respectively, the leg strap of each pair being connected to the opposite seat strap to provide a seat support for the aviator, a plurality of back straps connected to the upper portion of said main lift straps, each back strap extending diagonally across the wearer's back and terminating in thigh straps adapted to be connected to said leg straps and a single adjusting means interconnecting the ends of each of said thigh straps to simultaneously adjust said leg straps to aviators of different stature.

14. A parachute harness comprising a plurality of main lift straps arranged in pairs and adapted for attachment to a parachute, each pair of lift straps extending in front of the chest of the aviator and terminating in a leg strap and a seat strap respectively, the leg strap of each pair being connected to the opposite seat strap to provide a seat support for the aviator, a plurality of back straps connected to the upper portion of said main lift straps, each back strap extending diagonally across the wearer's back and terminating in thigh straps adapted to be connected to said leg straps, and a single adjusting means interconnecting each of said thigh straps to simultaneously adjust the leg strap and back straps to compensate for the difference in stature of different aviators.

15. A parachute harness comprising a plurality of main lift straps arranged in pairs, adapted for attachment to the parachute, the lower end of each pair of lift straps terminating in a leg strap and a seat strap respectively and cooperating with one another to form a seat support for an aviator, and means comprising auxiliary lift straps adapted to be readily detachably secured to said main lift straps to permit of the ready attachment or detachment of an emergency parachute.

16. A parachute harness comprising a plurality of main lift straps arranged in pairs and adapted for attachment to the parachute, each pair of lift straps terminating in a leg strap and a seat strap respectively, and cooperating with one another to form a seat support for an aviator, and adapter means readily attachably and detachably connected to said harness for securing an emergency back parachute thereto.

17. A parachute harness comprising a plu-

rality of main lift straps arranged in pairs and adapted for attachment to the parachute, each pair of lift straps terminating in a leg strap and a seat strap respectively, and cooperating with one another to form a seat support for an aviator, and adapter means for attaching an emergency parachute to the lift straps of said harness, said means comprising auxiliary lift straps for said emergency parachute and a readily attachable and detachable coupling means cooperating with said auxiliary lift strap adapted to be secured to the main lift straps of said parachute harness.

In testimony whereof I affix my signature.

EDWARD L. HOFFMAN.
